(57) **CLAIM**

The ornamental design for a vaporizer assembly, as shown and described.

DESCRIPTION

FIG. 1 is a top perspective view of a vaporizer assembly showing a first embodiment of my new design; FIG. 2 is a bottom perspective view of the design of FIG. 1; FIG. 3 is front elevation view of the design of FIG. 1; FIG. 4 is a back elevation view of the design of FIG. 1; FIG. 5 is a left side view of the design of FIG. 1; FIG. 6 is a right side view of the design of FIG. 1; FIG. 7 is a top plan view of the design of FIG. 1; and FIG. 8 is a bottom plan view of the design of FIG. 1; FIG. 9 is a top perspective view of a vaporizer assembly showing a second embodiment of my new design; FIG. 10 is a bottom perspective view of the design of FIG. 9;

FIG. 11 is front elevation view of the design of FIG. 9; FIG. 12 is a back elevation view of the design of FIG. 9; FIG. 13 is a left side view of the design of FIG. 9; FIG. 14 is a right side view of the design of FIG. 9; FIG. 15 is a top plan view of the design of FIG. 9; and, FIG. 16 is a bottom plan view of the design of FIG. 9. The broken lines in the drawings depict portions of the vaporizer assembly that form no part of the claim.

1 Claim, 12 Drawing Sheets
